WALTER WISMIEWSKI, OF SYRACUSE, NEW YORK, ASSIGNOR OF ONE-HALF TO
JOSEPH BARAMSKI, OF SYRACUSE, NEW YORK.

COMBINATION LOCK.

1,416,250.

Specification of Letters Patent. Patented May 16, 1922.

Application filed June 30, 1921. Serial No. 481,493.

To all whom it may concern:

Be it known that I, WALTER WISMIEWSKI, a citizen of the United States, and a resident of Syracuse, in the county of Onondaga and 5 State of New York, have invented a certain new and useful Combination Lock, of which the following is a specification.

This invention relates to combination locks and has for its object a particularly simple 10 and efficient lock mechanism by which the combination can be readily changed or re-adjusted and by which the lock mechanism can be operated by one knowing the combination without watching an index or dial. 15 The invention consists in the novel features and in the combinations and constructions hereinafter set forth and claimed.

In describing this invention, reference is had to the accompanying drawings, in which 20 like characters designate corresponding parts in all the views.

Figure 1 is an elevation of the lock mechanism embodying my invention, the casing or box therefor and contiguous parts being 25 shown in section and the handles being removed.

Figure 2 is a fragmentary elevation of parts seen in Fig. 1, the tumblers and lockings disks coacting therewith being shown 30 in unlocked position and parts being omitted.

Figures 3 and 4 are face views of the locking disks.

Figures 5 and 6 are edge views thereof.

Figure 7 is a sectional view, taken on the 35 plane of lines 7—7, Fig. 1.

Figure 8 is a sectional view taken on the plane of lines 8—8, Fig. 1, the disks being slightly displaced or rotated out of relative position they would assume in order to show 40 the pins or shoulders connecting the disks.

The combination lock comprises generally a movable tumbler and a plurality of locking disks coacting with the tumbler to normally hold it from unlocking movement and 45 having notches arranged to be brought into alignment with each other and with a portion of, as a projecting shoulder, or tail, of the tumbler, to permit unlocking movement of the tumbler, means connecting the disks by a 50 lost motion connection, a handle having a

shank on which the disks are mounted and a third disk mounted on the shank of the handle to rotate therewith, means connecting the third disk and one of the locking disks to transmit the rotary movement of 55 the handle to the locking disk, the third disk having a series of notches and a dwell or blank portion and a follower coacting with the notched periphery and dwell portion of the third disk. 60

The lock here illustrated, is shown as of double construction, that is, each half contains a tumbler and lock mechanism, which is a duplicate of the tumbler and lock mechanism of the other half. 65

1 designates the tumbler which is here shown as pivoted at 2 to a suitable casing or box 3, the tumbler having a tooth or shoulder 4, for coacting with the locking member 5 of the cover or door of the box or 70 cabinet provided with my lock, the tumbler also having a projecting shoulder or tail 6. The tumblers 1 of both sets are mounted on a common pivot 2 and as here shown, are normally pressed into their locking position 75 by spring arms 7 and are moved out of their locking position by suitable means as a cam 8 arranged between the tumblers and coacting on opposite sides of its axis with surfaces as 9, on opposing sides of the tumblers. 80

The cam 8, as here shown, is mounted upon a hollow sleeve, or stud 10, carried by a wall of the box or casing 3, and is operated by means of a handle 11 journaled in a suitable bearing 12 on the wall of the box 3 85 and having a shank 13 extending in the sleeve 10 and also having radial shoulders or pins 14 which interlock in notches 15 in the sleeve 8^a of the cam 8. The handle and its shank are held from removal by a screw 90 16 threading in the inner end of the shank and having its head thrusting against its shoulder as 17 at the bottom of a countersink in the inner end of the sleeve 10. The sleeve 10 has a shoulder 18 at its inner end which 95 prevents it from removal. 19 and 20 are the locking disks, said disks having their peripheries arranged to coact with the end of the tail 6 of the adjacent pawl 1 and having notches 21 and 22 arranged to come into 100

alinement with each other and with a tail 6 of the tumbler to permit pivotal movement of the tumbler to unlock the same. These disks are here shown as rotatably mounted 5 upon a sleeve 23 similar to the sleeve 10 and supported by the wall 24 of the box 3, and one of these disks is connected to the handle 25, the shank 26 of which is journalled in the sleeve 23. The disks 19 and 20 are connected 10 by a lost motion connection by means of which the disk 20, which is connected to the handle, can be rotated in one direction to take up the lost motion and then move the disk 19 therewith until its notch 21 is alined 15 with the tail 6 of the tumbler 1, and then can be rotated in the opposite direction relatively to the disk 19 until its notch 22 is alined with the notch 21 of the disk 19 and also with the tail 6 of tumbler 1. This lost 20 motion is here shown as provided for by pins or shoulders 27 and 28 on the opposing faces of the disks 19 and 20 and arranged in each other's path so that during turning of the disk 20 by the handle 25 the shoulder 28 25 first strikes or picks up the shoulder 27 and moves the disk 19 until the notch 21 thereof is alined with the tail 6 of the tumbler and then upon movement of the disk 20 in a reverse direction, the shoulder 28 moves away 30 from the shoulder 27. The shoulder 28 is one end of a pin 31 extending transversely through the disk 20.

The motion of the handle 25 is transferred to the disk 20 through a third disk 30 mounted on the sleeve 23 and connected to the disk 20 by means of a pin 31 extending through one of the series of holes 32 in the third disk 30 and in the hole in the disk 20, one end of this pin 31 serves as the shoulder 40 28, the third disk 30 is connected to the shank of the handle by means of a fourth disk 34 mounted on one end of the sleeve 23 to rotate thereon and having a hub 35 journalled in or extending into a hub 36 on 45 the walls of the casing 3, this hub 35 having a non-circular bore 37 and the shank of the handle 25 having a non-circular portion 38 fitting said non-circular bore 37. The fourth disk 34 is provided with a pin 39 which extends 50 into a hole 30^a in the disk 30. The combination required to operate the disks 19 and 20 can be varied by arranging the pin 31 in different holes 32.

The third disk 30 is provided with a series 55 of rounding teeth 42 on its periphery and with a blank or dwell portion 43, and a spring-pressed follower 44 coacts with these rounding teeth 42 and dwell portion 43. The followers 44 for both sets of locking mechanism are acted upon by a single spring 45 tending to move the respective followers 44 on their pivots 46 into engagement with the disk 30 on the two sets of locking mechanism.

In operation, assuming that the combination required to open the lock is, first, five

points to the right and seven points to the left, the operator first brings the knob or handle 25 of one lock mechanism until the follower is on the dwell portion 43 of the disk 30. He then turns the handle five 70 notches to the right as indicated to the sense of touch, due to the follower 44 ratcheting over the rounding teeth 42, such movement brings the notch 21 on the disk 19 into alinement with the tail 6 of the corresponding 75 tumbler 1. He then turns the handle in the opposite direction, moving the disk 20 relatively to the disk 19 which remains stationary by reason of the extreme tip of a tail 6 being partly in the mouth of the notch 21, the operator turning the handle seven notches to the right, thereby bringing the notch 22 on the disk 20 into alinement with the tail 6 of the corresponding tumbler. The same operation is performed on the other set of locking mechanism, either with the same combination or with any other combination, it is desired to use. He then turns the handle 11 moving the tumblers 1 out of engagement 80 with the locking part 5 so that the box or 85 cabinet can be opened.

What I claim is:

In a combination lock, the combination of a pair of tumblers mounted upon a common axis and having shoulders on opposite sides 95 of said axis, a spring mounted on said axis and tending to move them into operative position, an operating member mounted between the tumblers and acting to force the same on their pivots out of operative position, sets of rotary disks, each set arranged with their peripheries engaged with one of the shoulders to prevent movement of the tumblers, the disks having peripheral notches arranged to be brought into alinement with each other and with the shoulder of one of the tumblers for permitting movement with the tumbler with which the shoulder is associated, a handle for each set of disks, the handle having a shank, the disks 100 being mounted concentric with the shank, a third disk associated with each set, and mounted concentric with the shank of the handle and connected thereto to rotate therewith, means for permanently connecting the 105 third disk to one of the notched disks, means for connecting the notched disks together by a lost motion connection whereby movement in one direction of the notched disk connected to the third disk takes up the lost 110 motion and rotates the other notched disk therewith and permits movement of the notched disk connected to the third disk in the opposite direction relatively to the other notched disk, each third disk having a series 115 of rounding notches and a dwell portion, a pair of spring pressed followers arranged between the third disk and below the axis of the tumblers and coacting with the notches and the dwell portion of the third disks re- 120 125 130

spectively, and being normally engaged with said dwell portion, and the disk connected to each third disk being connected to the third disk to permit that disk connected to the 5 third disk to be adjustably shifted relatively to the third disk without changing the position of the third disk whereby the follower normally engages the dwell portion of

the third disk in all changes of the combination.

In testimony whereof, I have hereunto signed my name, at Syracuse, in the county of Onondaga, and State of New York, this 22nd day of June, 1921.

WALTER WISMIEWSKI.
